UNITED STATES PATENT OFFICE.

HARRY A. MARX, OF PORT HURON, MICHIGAN.

INTERCHANGEABLE CROWN.

1,174,886.

Specification of Letters Patent. Patented Mar. 7, 1916.

Application filed February 10, 1915. Serial No. 7,292.

To all whom it may concern:

Be it known that I, HARRY A. MARX, a citizen of the United States, and a resident of Port Huron, county of St. Clair, State of Michigan, have invented certain Improvements in Interchangeable Crowns, of which the following is a specification.

My invention relates to artificial teeth and one object thereof is to provide a porcelain or other crown of such construction that while being applicable to a suitably formed backing so as to be rigidly held from movement, it is structurally strong and its connection with said backing is of such a nature that it is not likely to become loosened or break.

I further desire to provide a crown or artificial tooth which shall be provided with a transverse groove and an adjacent plane surface both of which are ground after baking to standard dimensions in order that said crown may fit a standard backing plate and be interchangeable with other teeth of the same form but of different coloring.

Another object of the invention is to provide a novel form of crown and backing therefor which shall not only be slightly but shall be of a strong construction and easily assembled and applied to dental bridge work.

These objects and other advantageous ends I secure as hereinafter set forth, reference being had to the accompanying drawings in which—

Figure 1 is a perspective view of a crown or artificial tooth constructed according to my invention; Fig. 2 is a perspective view of the preferred form of backing employed with the tooth shown in Fig. 1; Figs. 3 and 4 are respectively a vertical section and a plan of the tooth shown in Fig. 1, and Figs. 5 and 6 are respectively a perspective view and a vertical section of another form of tooth showing my invention as applied thereto.

In Figs. 1, 3 and 4 of the above drawings, 1 represents an artificial tooth of porcelain or other suitable material, whose biting surface 2 and whose front surface 3 are formed to resemble as closely as possible the same portions of a natural tooth, while that portion 4 of the back surface of the tooth, which intersects the biting surface, likewise has a natural form. The tooth or crown is also formed with a plane inner or lingual surface 5 extending from the rear surface 4

to a surface 6 whose edge distant from the biting surface intersects the front surface 3 of the crown. At or adjacent the line of intersection of the two surfaces 5 and 6, I provide a groove 7 extending transversely of the tooth in the thickest portion thereof and having a rectangular section, its arrangement being such that its bottom is substantially parallel with the plane of the rectangular surface 5.

According to my invention the surface 5 and the walls of the groove 7 are accurately ground to standard dimensions after the tooth is baked so that any tooth will accurately fit a suitably formed backing such as that shown in Fig. 2. This backing consists of a flat metal plate 8 preferably of uniform thickness having along one edge a projecting rib 9 of rectangular section of such dimensions as to closely fit the transverse groove 7 of any of the teeth constructed according to my invention, at the same time that the flat body portion 8 likewise accurately fits upon the base of the lingual surface 5.

The outline of the plate 8 may be made to conform more or less closely to the outline of the surface 5 and a post 10, preferably projecting from the central portion of the rib 9, is designed to enter a suitably placed hole 11 in the tooth or crown 1. It is to be noted that the groove 7 is so placed that it extends transversely of what is the thickest and therefore the strongest part of the crown, and that the hole for the post 10 likewise extends at right angles to the line of this groove into the thick central part of the tooth.

While in Figs. 1, 3 and 4 I have shown a molar tooth or crown constructed according to my invention, I have illustrated in Figs. 5 and 6 an incisor tooth formed with the plane lingual surface 5^a and a transversely extending groove 7^a having its bottom parallel with said surface. In this case a plane surface 12 extends from the front surface of the tooth, back to the front wall of the groove 7^a at a more or less acute angle to the plane of the surface 5^a.

In any case it is to be noted that the base 5 of the lingual surface, the walls of the slot 7 and the post receiving hole 11 are ground to standard sizes so that any tooth will accurately fit the standard backing, the post hole 11 preferably projecting forwardly into the front portion of the body

of the tooth in a line inclined to the plane of the surface 5.

One very obvious advantage of my invention resides in the possibility of the convenient substitution of one tooth for another on a given backing or bridge and it is to be noted that by the use of teeth and backing made according to said invention I am enabled to do away with metallic biting surfaces and that without materially weakening the porcelain structure constituting the crown or tooth.

I claim;—

The combination of a substantially flat and transversely continuous backing plate, having an offset transverse rib of substan-

tially rectangular cross section; a crown having a continuous plane surface for the reception of the corresponding part of said plate and formed with a transverse groove of substantially rectangular section for the reception of the rib on the plate, said plate having a post extending from said rib into the crown.

In testimony whereof, I have signed my name to this specification, in the presence of two subscribing witnesses.

HARRY A. MARX.
